UNITED STATES PATENT OFFICE.

EDWARD C. INDERLIED AND CHARLES B. RUMSEY, OF BINGHAMTON, NEW YORK; SAID RUMSEY ASSIGNOR TO SAID INDERLIED.

HEATING APPARATUS.

SPECIFICATION forming part of Letters Patent No. 653,867, dated July 17, 1900.

Application filed April 25, 1900. Serial No. 14,324. (No model.)

To all whom it may concern:

Be it known that we, EDWARD C. INDERLIED and CHARLES B. RUMSEY, citizens of the United States, residing at Binghamton, 5 in the county of Broome and State of New York, have invented certain new and useful Improvements in Heating Apparatus; and we do hereby declare the following to be a full, clear, and exact description of the invention, such as will enable others skilled in the art to which it appertains to make and use the same.

Our invention has for its object the generation of heat and its utilization in the arts generally. It is particularly applicable to the conversion of a liquid into a vaporous state in a steam-boiler, in the process of dry distillation, &c., and also to the decomposition of matter, such as coal, in the manufacture of coke, gas, &c.

The invention in the most generic sense comprises two substantially-parallel pipes, one for gas and the other for air, closed at one of their ends and provided with perforations along their sides, in combination with a combustion-chamber surrounding the same, said chamber being provided with a suitable exit for the products of combustion, but otherwise closed or sealed.

30 In its more limited sense the invention involves the idea of internal location of the combustion-chamber relative to the matter to be operated upon and includes also means for heating the air and forcing it under pressure to the combustion-chamber, all of which will be hereinafter more fully described, and particularly stated in the claims.

In the drawings, Figure 1 is a vertical longitudinal sectional view of one form of boiler, showing our device applied thereto; Fig. 2, a vertical transverse section of the same; Fig. 3, a vertical section of another form of boiler, showing our device applied thereto; Fig. 4, a transverse section of the same, taken through the center of the combustion-chamber; and Fig. 5, a vertical transverse sectional view of a charged retort, showing the location of combustion-chamber and gas and air pipes situated therein and 50 the return-pipes for the products of combustion.

Referring to the several views, the letter A indicates a boiler, which may be either of a horizontal or upright type, and B a retort. Each device is provided with a suitable heat-insulator *b* and is mounted upon a suitable base, which is formed with an air-chamber having an inlet for the admission of air. The several devices and their bases may be of any desired construction, so long as the base of each is formed with an air-chamber.

The letter D indicates a combustion-chamber, preferably circular in cross-section and of considerable length relative to its cross-sectional area. This chamber is provided 65 with three openings, two of which serve as ingress-openings for the fuel elements and the other as the egress-opening for the products of combustion and is otherwise closed or sealed. It may be stated that this chamber need not of necessity be a part of the burner structure, but may be formed by the apparatus containing the matter to be operated upon, or may, in fact, be a part of said matter—as, for example, when it is desired 70 to heat a broken pipe for repairs said pipe may itself be made to form the combustion-chamber.

Within the combustion-chamber are the gas and air pipes E and F, respectively. 80 These pipes are perforated along their sides, closed at one of their ends, and preferably extend substantially the length of the combustion-chamber. The perforations of the gas and air pipes should for the best results 85 be so arranged that the jets of one will cross those of the other pipe.

G indicates a fuel-supply tank which communicates with the gas-pipe. The fuel used may be either a fixed gas or liquid fuel 90 adapted to be vaporized and introduced into the combustion-chamber in a vaporous state.

H indicates a fan having communication with the air-pipe and adapted to force air under pressure therethrough into the combustion-chamber.

In order to utilize to the greatest degree the heat generated, we have provided an air-heating chamber I, through which the products of combustion are caused to pass before 100 escaping into the atmosphere, said air while in its heated state being introduced into the

combustion-chamber by the means above described. The air-heating chamber is provided with a suitable air-inlet *i* and an outlet *i'*.

Situated within the heating-chamber is a coil *K*, having communication with the egress-opening of the combustion-chamber and opening out into the atmosphere through the wall of said air-heating chamber. It will be understood, however, to those skilled in the art that the air may be caused to pass through the coil and the products of combustion through the chamber containing the coil.

In order to produce perfect combustion, the volume of air introduced to the combustion-chamber must far exceed the volume of gas. By the construction and arrangement of the parts herein described the air passing through the perforations of the air-pipe in jets at a high velocity and crossing the gas-jets tends to communicate thereto motion in the same direction, resulting in a more thorough agitation and intermingling of the fuel elements. Moreover, as the pressure of the air-jets is communicated in all directions in the combustion-chamber it follows that those nearest the egress-opening tend to retard the escape of the gases in other parts of the combustion-chamber, whereby the fuel elements are held for a longer period within the heat zone, resulting in their more complete combustion.

Having thus fully described our invention, what we claim, and desire to secure by Letters Patent, is—

1. The combination of a combustion-chamber having an egress-opening, two perforated fuel-pipes, closed at one end, situated in the combustion-chamber and extending its length, said combustion-chamber being of such cross-sectional area as to provide but a limited space surrounding the fuel-pipes, so that the fuel elements issuing from the pipes and the products of combustion are forced to move longitudinally thereof toward the egress-opening, means for introducing gas to one of said pipes and means for introducing air to the other of said pipes.

2. The combination of a combustion-chamber provided with an egress-opening and perforated gas and air pipes situated in the chamber and extending its length, said combustion-chamber being of such cross-sectional area as to provide but a limited space surrounding the fuel-pipes, so that the fuel elements issuing from said pipes and the products of combustion are forced to move longitudinally thereof toward the egress-opening, the air and gas being introduced to the combustion-chamber under pressure.

3. The combination of a combustion-chamber provided with an egress-opening, perforated gas and air pipes situated within the combustion-chamber and extending longitudinally its length, said combustion-chamber being of such cross-sectional area as to provide but a limited space surrounding the fuel-pipes, so that the fuel elements issuing from

said pipes and the products of combustion are forced to move longitudinally thereof toward the egress-opening, the perforations in said pipes being so arranged that the jets issuing from one pipe will cross those issuing from the other.

4. The combination of a chamber to contain the matter to be heated, a combustion-chamber arranged therein and completely surrounded by the said matter, said combustion-chamber being provided with an exit-opening, perforated gas and air pipes, closed at one end, situated within the combustion-chamber and extending longitudinally its length, the said combustion-chamber being of such cross-sectional area as to provide but a limited space surrounding the gas and air pipes, so that the fuel elements issuing from said pipes and the products of combustion are forced to move longitudinally thereof toward the egress-opening, and means for supplying gas and air respectively to said pipes.

5. The combination of a chamber to contain the matter to be heated, a combustion-chamber so arranged therein as to be completely surrounded by the said matter, said combustion-chamber being provided with an exit-opening, perforated gas and air pipes situated within the combustion-chamber and extending longitudinally thereof, said pipes being closed at one end and having perforations along their sides, said perforations being so arranged that the jets issuing from one will cross those of the other, the said combustion-chamber being of such cross-sectional area as to provide but a limited space surrounding the gas and air pipes, so that the fuel elements issuing from said pipes and the products of combustion are forced to move longitudinally thereof toward the egress-opening, and means for supplying gas and air respectively to said pipes.

6. The combination of a chamber to contain the matter to be heated, a combustion-chamber so arranged therein as to be completely surrounded by the said matter, the combustion-chamber being provided with an exit-opening, perforated gas and air pipes situated within the combustion-chamber and extending longitudinally its length, the pipes being closed at one end, the said combustion-chamber being of such cross-sectional area as to provide but a limited space surrounding the gas and air pipes, so that the fuel elements issuing from said pipes and the products of combustion are forced to move longitudinally thereof toward the egress-opening, means for supplying gas and air respectively to said pipes under pressure.

7. The combination of a chamber to contain the matter to be heated, a combustion-chamber so arranged therein as to be completely surrounded by the said matter, the combustion-chamber being provided with an exit-opening, perforated gas and air pipes situated within the combustion-chamber and

extending longitudinally its length, the pipes being closed at one end, the said combustion-chamber being of such cross-sectional area as to provide but a limited space surrounding the gas and air pipes, so that the fuel elements issuing from the said pipes and the products of combustion are forced to move longitudinally thereof toward the egress-opening, means for supplying gas and air respectively to said pipes, and means for heating the air supplied.

8. The combination of a chamber to contain the matter to be heated, a combustion-chamber so arranged therein as to be completely surrounded by the said matter, the combustion-chamber being provided with an exit-opening, perforated gas and air pipes situated within the combustion-chamber and extending along the length thereof, the said combustion-chamber being of such cross-sectional area as to provide but a limited space surrounding the fuel-pipes, so that the fuel elements issuing from said pipes and the products of combustion are forced to move longitudinally in the direction of the egress-opening, means for introducing gas to one of

said pipes and means for introducing heated air to the other of said pipes.

9. The combination of a combustion-chamber having an egress-opening, two perforated fuel-pipes, closed at one end, situated within the combustion-chamber and extending its length, said combustion-chamber being of such cross-sectional area as to provide but a limited space surrounding said pipes, so that the fuel elements issuing from the pipes and the products of combustion are forced to move longitudinally thereof toward the egress-opening, an air-heating chamber, means for conveying the products of combustion through said air-chamber, means for introducing gas to one of said pipes, and means for introducing heated air from said air-heating chamber to the other of said pipes.

In testimony whereof we affix our signatures in the presence of two witnesses.
